UNITED STATES PATENT OFFICE.

WILLIAM C. RASTETTER, OF FORT WAYNE, INDIANA.

FOLDING CHAIR.

Application filed February 6, 1925. Serial No. 7,424.

This invention relates to improvements in folding chairs and the object thereof is to provide a chair of its class, the legs and seat of which when in position for use, will be rigidly sustained and firmly support the occupant, and the back of which will be held in such manner as to conform to the body of the occupant. Another object of the invention is to provide an attractive and serviceable folding chair so constructed as to admit of economical manufacture.

These objects are accomplished by the construction illustrated in the accompanying drawings, in which:—

15 Fig. 1 is a side elevation of a chair embodying the invention; and

Fig. 2 is a front elevation projected from Fig. 1.

The characters appearing in the description refer to parts shown in the drawings and designated thereon by corresponding characters.

The invention comprises a pair of frame members 1, the respective lower portions of which constitute the fore legs 2 of the chair, and the upper portions forming corresponding side arms 3. The legs 2 are connected by a suitable brace member 4, and the arms are connected near their upper ends by a transverse rod 5. Also, said frame members are connected together centrally by a transverse rod 6 upon which is pivotally mounted a seat 7, the rod 6 forming a fulcrum therefor. A pair of rear legs 8 are mounted pivotally upon the rod 6 which passes through the respective rear legs near their upper ends which ends are interposed between the sides of the seat and the frame members correspondingly.

40 A pendant prop 9 is pivotally supported on each arm 3, the lower end of the prop having therein an elongated slot 10 through which a transverse rod 11 connecting the legs 8 extends. A washer 12 is positioned on the rod 6 between each side of the seat 7 and the adjacent leg 8 so that the seat is spaced apart from the legs 8 for the accommodation of the props 9 when the chair is folded. The props are connected by a cross-bar 13 at a point above the level of the seat 7, and the rear end 14 of the seat extends rearwardly between the props and bears upwardly against the cross-bar 13 when the seat is in position for use. A shackle loop 15 in each side of the seat near the rear end thereof extends around the adjacent prop 9,

which passes loosely therethrough, so that when the front end of the seat is raised, its rear end swings downwardly and the shackles bear against the props causing the 60 props to swing inwardly.

A back member 16 is pivotally mounted on the transverse rod 5 between the arms 3, the rod 5 serving as a fulcrum bearing for the back. At each side of the back member 65 near the lower end thereof is a shackle loop 17 through which the corresponding prop 9 loosely extends so as to admit of limited pivotal movement of the back member on the rod when the chair is in position for use. 70

A pair of cross-braces 18 are secured at their respective upper ends on the seat rod 6, and with their corresponding opposite ends on the cross-rod 11 that connects the folding legs. The cross-braces serve to restrain 75 the folding legs from lateral swinging movement.

In utilizing the invention the chair is placed in position for use by swinging the seat upon its fulcrum to horizontal position, and the props are swung backwardly by the shackle loops on the seat, and the folding legs 8 are likewise swung backwardly through the action of the props. 80 Also, the back member is tilted upon its fulcrum support by the props which act in conjunction with the shackle loops on the back member. When the occupant assumes position on the seat the back member tilts upon its fulcrum support to an extent limited by 85 the shackle loops thereon and conforms to the angle of the body of the occupant accordingly. Also, because of the weight of the occupant on the seat, the rear end of the seat bears upwardly against the cross-bar 13 on the props which lends rigidity to the side frame members and the folding legs through the medium of the props connected therewith. 90

What I claim is:—

1. In a folding chair, a pair of side frame members spaced apart; a transverse rod connecting said members centrally; a pair of folding legs on said rod respectively adjacent the inner faces of the corresponding frame members; a seat having pivotal support on said transverse rod between said legs; a pendant prop having pivotal connection with each of said frame members at a point thereon above the seat; a transverse bar connecting said props at points thereon above said seat; a shackle loop on each side 100

100

105

110

- of the seat adjacent the rear end thereof, each loop encompassing the adjacent prop; a back member having pivotal support in connection with said side members so as to 5 turn upon a horizontal axis above said props; and a shackle loop on each side of the back member adjacent the lower end thereof encompassing respectively the adjacent prop, said loops having limited movement on said props.
- 10 2. In a chair including a pair of side frame members and folding rear legs pivoted in connection therewith, a pair of prop members having pivotal connection at their tops 15 respectively with the corresponding frame members at points thereon above said legs, said prop members having connections respectively with said legs in the lower portions thereof and having limited sliding movement relative thereto; a seat fulcrumed 20 between the frame members and having limited sliding movement relative to said props; and a back member having ful-
- crumed support in connection with the frame members at points thereon above the props, 25 and having sliding engagement adjacent its lower end with said props.
3. In a folding chair having a folding seat and legs in supported relation with side frame members, a pair of props pivoted in 30 connection with said frame members and having sliding connections respectively with said folding legs and limited movement relative thereto, said seat having sliding connections adjacent its rear end with said 35 props and limited movement relative thereto; and a back member having fulcrumed support between the side frame members at points thereon above the props, and having sliding connections adjacent its lower end with said prop members and limited movement relative thereto.

40 In testimony whereof I affix my signature.

WILLIAM C. RASTETTER.
